DUMP VALVE FOR A CIRCUIT BREAKER
PNEUMATIC MOTOREdwin C. Goodwin, Canton, Mass., assignor to
Allis-Chalmers Manufacturing Company, Mil-
waukee, Wis., a corporation of Delaware

Application May 14, 1948, Serial No. 27,076

6 Claims. (Cl. 200—82)

1

The invention relates to circuit breakers, and more particularly to pneumatically operated high speed circuit breakers.

An object of the invention is the provision of an improved pneumatic circuit breaker operating mechanism of the cylinder piston type capable of effecting high speed opening and reclosing of the circuit breaker.

Another object of the invention is to provide a pneumatic circuit breaker operating mechanism of the cylinder piston type comprising improved means for exhausting gas under pressure from the cylinder.

Circuit breakers for electrical power systems are required to operate at very high speed. This can be achieved by use of pneumatic operators of the cylinder piston type. Such operators require provision of dumping means for causing quick collapse of gas pressure in front of the piston tending to reduce the speed of movement thereof. Effective dumping of compressed gas from the cylinder of a pneumatic operator of the cylinder piston type is of particular importance wherever it is desired to effect a rapid reversal of the movement of the piston. In case of reversal of the movement of the piston of a pneumatic motor supposed to operate at high speed, compressed gas should be dumped instantly from back of the piston preparatory to reversal of its movement.

In order to achieve dumping in a reliable uniform manner at each stroke of the piston requiring dumping, the point of time at which dumping is to take place must be predetermined with great accuracy, and dumping must take place rapidly thereafter. Reliability of operation calls for a self-sufficient circuit breaker operating system, i. e., one wherein the time at which dumping is initiated and during which it is effected is solely dependent upon operating conditions of, and within, the pneumatic operator rather than upon any extraneous conditions or means as, for instance, upon conditions of electric circuits, or upon the presence of an electric relay. In addition to the foregoing reliability of operation requires that pressure conditions within the cylinder in the process of being vented be made the controlling factor as to maintaining the dumping means effective upon initiation thereof, and as to permitting the dumping means to become ineffective to allow renewed refilling of the cylinder with compressed gas. It is, therefore, another object of the invention to provide a self-sufficient pneumatic circuit breaker operating mechanism of the cylinder pis-

2

ton type wherein the time at which dumping is initiated is determined by the relative position of piston and cylinder, and wherein the time during which the dumping means are maintained effective is determined by the pressure that the gas in the process of being dumped from the cylinder is capable of exerting.

Different circuit breakers may have different mechanical systems having different masses, and 10 may differ in many other respects, yet such different breakers may lend themselves to operation by a standard pneumatic operator, provided that the operator permits rapid dumping of compressed gas from back of the piston at different but exactly predetermined times before the piston has completed its potential stroke. In case 15 of closing of a circuit breaker the piston must be accelerated for a sufficient time to obtain the required speed of operation. Pressure of compressed gas upon the piston must also be maintained sufficiently long to achieve safe latching-in of the mechanism provided for restraining the breaker in closed circuit position. In order to 20 permit rapid reversal of the movement of the piston gas pressure should not be maintained within the cylinder longer than necessary to meet these requirements. The point of time at which dumping is to be initiated is relatively critical and varies from circuit breaker to circuit breaker. 25 It is, therefore, a further object of the invention to provide a standard pneumatic circuit breaker operating system which can be applied to different circuit breakers and can readily be adjusted to the critical dumping time required for achieving 30 best results in any particular application, and in which a self-adjustment of the time during which the dumping means are maintained effective in any particular application is achieved by controlling the dumping process by the pressure of the gas in the process of being dumped from the pneumatic motor.

Circuit breakers for electrical power systems comprise a linkage which is supposed to be latched-in when the piston is in closed circuit 35 position so as to preclude the contacts of the circuit breaker to part. If a breaker is being closed by a pneumatic operator and the latching means fail to restrain the linkage and the contacts in closed circuit position, the contacts, which are biased to an open circuit position, are allowed to part. In that particular case parting of the contacts may occur at a very slow speed on account of a decelerating or dashpot action of the pneumatic operator. Parting of the contacts at a small speed results in prolonged arc-

ing. In the case under consideration, the arcing time may well be sufficiently long to endanger both the system into which the breaker is connected as well as the breaker itself. It is, therefore, another object of the invention to provide means which become operative as often as latching-in is to occur for precluding damage to the breaker as well as to the system into which the breaker is connected in case of a latch failure.

Another object of the invention is the provision of an improved circuit breaker operating mechanism that comprises a linkage of the trip free type for operating the breaker and latching means for latching the linkage to restrain the breaker in closed circuit position, and that further comprises a pneumatic motor of the cylinder piston type having means for returning the piston to its initial position instantly upon completion of each closing operation.

Another object of the invention is to provide an improved pneumatic operating mechanism for circuit breakers which lends itself to rapid reclosing duty, is simple, safe and reliable in operation, and inexpensive to manufacture.

Other objects and advantages of the invention will become apparent from the following description when read in connection with the accompanying drawing, in which:

Fig. 1 is a view, partly in section, of a circuit breaker operating system embodying the present invention, the circuit breaker being shown somewhat diagrammatically;

Fig. 2 is a fragmentary sectional view showing on a larger scale the dump valve and the means for its control; and

Figs. 3 to 5 show in front elevation three different positions of the linkage by which the circuit breaker is operated and restrained in closed circuit position.

Referring now to Fig. 1 of the drawings, reference sign 1 indicates generally a pneumatic motor of the cylinder piston type for operating the circuit breaker. The latter has been generally indicated by reference sign 3. Motor 1 and circuit breaker 3 are operatively related by a linkage which has been generally indicated by reference sign 2.

As diagrammatically shown, the circuit breaker 3 comprises a pair of stationary contact members 4 and a movable contact member 5. The circuit breaker is biased to open circuit position by means of accelerating spring 6. The movable contact member 5 is supported by a breaker rod 7 which, in turn, is supported by lever 8 pivoted at 9. Lever 8 is connected to bellcrank lever 10 by means of operating rod 11. Bellcrank lever 10 is pivoted at 12 and forms part of linkage 2.

Motor 1 comprises the main casting 12 defining the lateral wall of the operating cylinder of the motor, the top element 13 and the base element 14. Piston 15 of motor 1 is biased in a downward direction by a helical spring 16 of which one end rests against top element 13, while its other end rests against piston 15. Base element 14 defines a passage 17 for admitting gas under pressure from a suitable source of gas under pressure (not shown) to the cylinder of motor 1. The flow of gas under pressure from said source to the cylinder of motor 1 may be controlled by a suitable valve (not shown), preferably a solenoid operated valve. Upon admission of gas under pressure to motor 1, piston 15 is raised against the bias of spring 16. Piston 15 is provided with a ram or plunger 18 adapted to cooperate with a roller 19 forming part of linkage 2. Upon raising of piston

15, the parts by which linkage 2 is constituted are moved to their position shown in Fig. 1, which causes engagement of contacts 4 and 5 of breaker 3. Linkage 2 is now being latched-in by latching means which are fully described below, and thus linkage 2 restrains circuit breaker 3 in the closed position thereof against the bias of accelerating spring 6. When breaker 3 is closed, piston 15 and ram 18 are free to move to their initial position shown in Fig. 1 under the combined action of gravity and spring 16.

There are certain instances where it is desired to close a circuit breaker manually without resorting to the operation of a pneumatic motor. To comply with that requirement, cylinder base 14 is provided with a bearing 14a adapted to receive a plunger 19. Plunger 19 may be operated by means of a hand closing jack (not shown) to close circuit breaker 3.

Linkage 2 includes a bellcrank lever 20 pivoted at 21 and connected by pin 22 to toggle link 23. Lever 20 and toggle link 23 form a toggle 20, 23 which is slightly off center in the closed position of the breaker (shown in Fig. 1) and which may be caused to collapse (as indicated in Figs. 3 and 4) on occurrence of a fault in the system into which the breaker is connected. The center pin 22 of toggle 20, 23 supports the above referred to roller 19 adapted to be acted upon by the plunger or ram 18 on piston 15. The right end of link 23, as viewed in Fig. 1, is pivoted at 24 to a floating lever 25. Link 26 interconnects floating lever 25 and bellcrank lever 10. The main latch 27 is pivotally supported at 28 by stationary bracket 29 and acted upon by compression spring 30 of which one end bears against the main latch 27 while the other end bears against bracket 29. The lower end of main latch 27 is adapted to engage a latch plate 31 forming an integral part of bellcrank lever 20. The upper end of main latch 27 constitutes an abutment 32 adapted to be engaged by a cooperating abutment 33 on latch 34. Latch 34 is pivoted at 35 and acted upon by a compression spring 36 tending to pivot it in a clockwise direction about pin 35. As viewed in Fig. 1, the right side of latch 34 is provided with a cam surface 37 adapted to engage a roller 38 carried by floating lever 25 by means of pin 39. Upon release of roller 38 by cam surface 37, floating lever 25 is free to move under the action of accelerating spring 6, and this permits separation of contacts 4 and 5 of circuit breaker 3.

When roller 38 has been released by cam surface 37, pin 39 moves from left to right along a substantially straight path defined by guiding means 40. Latch 34 is also provided with a straight cam surface 41 adapted to engage roller 38 during the interrupting process of the circuit breaker, as will be seen more clearly as the description progresses. An upper cam surface 42 on latch 34 rests against a latch 43 pivoted at 44 and acted upon by biasing spring 45 tending to pivot it in a clockwise direction about pin 43. Latch 42 is held in position by a latch 46 engaged pin 47 on latch 42. Latch 45 is pivoted at 48 and biased in a counterclockwise direction by spring 49. The left arm of latch 45 is adapted to be pulled in an upward direction by a solenoid or a similar electroresponsive means 50, thus causing latch 45 to pivot about pin 47 in a clockwise direction. Lever 51 is pivotally mounted on pin 52 and adapted to engage lever 53 which is pivotally mounted on pin 54. Lever 52 is spring biased in a clockwise direction. Upon pivoting of lever 51 in a clockwise direction about pin 52

(which may be effected manually), lever 52 is pivoted against the action of its biasing spring in a counterclockwise direction about pin 53. This causes latch 45 to be pivoted in a clockwise direction about pin 47 which, in turn, initiates separation of contacts 4 and 5 under the action of accelerating spring 6. The separation of contacts 4, 5 may be initiated in a similar way by energizing the relay or solenoid 49 in response to the occurrence of a fault in the system into which the breaker is connected.

A resetting compression spring 55 is arranged below the linkage and latching mechanism 2 of the breaker and biases bellcrank lever 20 in a clockwise direction. When the breaker is tripped as indicated in Fig. 3, the linkage and latch system 2 will be reset by the action of spring 55, thus assuming the position shown in Fig. 4.

In order to close the breaker, compressed gas is admitted to fluid motor 1 through passage 17, thus causing piston 15 and ram 18 to move in an upward direction. The closing force of motor 1 is applied to linkage 2 by engagement of ram 18 with roller 19. Fig. 4 shows the linkage mechanism in open position. Toggle 20, 23, in moving up, rotates floating lever 25 about pin 39 as a center. That rotary motion of lever 25 causes raising of the left side of link 26. This, in turn, causes bellcrank lever 10 to rotate in a clockwise direction about pin 57 as a center, pulling connecting rod 11 down and breaker rod 7 up, thereby closing the breaker against the action of accelerating spring 6.

As mentioned above, tripping may be initiated either mechanically by raising the left end of lever 50 or electrically by energizing trip solenoid 49 operable in response to predetermined circuit conditions. The armature of trip solenoid 49 lifts latch 45 against the reaction of cam latch 42. The resulting clockwise rotation of latch 45 about pivot 47 releases pin 46 on latch 42. Thus latch 42 is free to rotate under the action of large latch 34 applied through upper cam surface 41. Latch 42 thereby slides off large latch 34 as large latch 34 starts to rotate in a counterclockwise direction about pin 35 under the action of roller 38 which is acted upon by the powerful accelerating spring 6. The counterclockwise rotation of latch 34 against the bias of spring 36 permits the top end of floating lever 25 to move to the right. As pin 39 on lever 25 moves to the right it slides in guiding means 40. That movement of lever 25 and pin 39 permits parts 7, 8 and 11 of breaker 3 to move to open circuit position.

Rotation of latch 34 in a counterclockwise direction about pin 35 causes abutment 33 to engage abutment 32 on main latch 27, thereby rotating main latch 27 in a clockwise direction about pin 28. Thus main latch 27 becomes disengaged from latch plate 31 on bellcrank lever 21.

Fig. 3 shows the position of the parts of the linkage and latch system 2 shortly upon initiation of the tripping process but before completion thereof. Fig. 4 shows the position of the parts of the linkage and latch system 2 upon completion of the tripping process. At the beginning of the tripping process, pin 39 moves in guiding means 40 from left to right. Upon release of latch plate 31 by main latch 27, resetting spring 55 causes a clockwise rotation of bellcrank lever 20 about pin 21 which, in turn, causes collapse of toggle 20, 23, resulting in a movement of pin 39 in guiding means 40 from the right to the left, as shown in Fig. 4. While pin 39 moves from left to right, and then back to the left, the 75

straight cam surface 54 of latch 34 rests against the top of roller 38. Upon return of pin 39 and roller 38 to their original left position, latch 34 drops in place under the action of compression spring 36. This allows the balance of the system, including latches 42 and 45, to reset, as shown in Fig. 4. With the parts of the linkage and latch system 2 back in the position shown in Fig. 4, the operator is ready for the next closing operation.

A closing operation is completed when main latch 27 has engaged latch plate 31. Then the supply of compressed gas may automatically be shut off. This may be achieved, for instance, by a limit switch (not shown) controlled by shaft or pin 21. Assuming now that there is a main latch failure, i. e., that either the main latch 27 or the latch plate 31 are so badly damaged (either broken or worn out) that they fail to restrain the breaker in the closed circuit position. The breaker will then reopen under the action of accelerating spring 6, but its opening movement might be relatively slow on account of the decelerating action, or dashpot action, of fluid motor 1. Even if the supply of compressed air is shut off from motor 1 and the lower side of the motor 1 is being vented to atmosphere by prior art venting means, the decelerating effect of motor 1 might be too large and the speed of separation of the contacts 4, 5 too small to achieve a safe interruption of the circuit controlled by the breaker. The dumping means shown in Figs. 1 and 2 are, however, so effective as to preclude any danger in case of complete failure of latching means 27 and 31.

As shown in Figs. 1 and 2, dumping of air admitted through passage 17 to cylinder 12 may be effected by a piston type valve which has been generally indicated by reference sign 58. Valve 58 comprises a cylindrical valve body 59 which forms an integral part of piston 15 of motor 1. Valve element 60 is movably arranged within valve body 59 and biased to a closed position by means of helical spring 61. Valve element 60 is in the shape of a piston and one end of spring 61 rests against the inner side thereof, while the other end of spring 61 rests upon the base of valve body 59. Piston 15 is provided with bores defining a passage 62 for admission of compressed gas from the portion of cylinder 12 situated below piston 15 to valve 58. The top of valve element 60 is provided with a valve stem 63 adapted to cooperate with an abutment 64 upon reaching by piston 15 of a predetermined position within working cylinder 12. Engagement of stem 63 and abutment 64 results in initial opening of valve 58 against the bias of spring 61. Upon initial opening of valve 58 gas under pressure below piston 15 is free to flow through passage 62, the space within valve 58 above valve element 60 and a passage 65 provided in piston 15. Compressed gas which is admitted through passage 65 to the portion of the cylinder 12 above piston 15 is quickly dumped from that space through a permanently open passage 66 in cover plate 13. Upon initial cracking of valve 58 by engagement of stem 63 and abutment 64 a high pressure zone forms on top of valve element 60 tending to maintain valve element 60 in its open position against the bias of spring 61. Thus valve element 60 remains safely in its open position when, as a consequence of the reversal of the movement of piston 15 under the action of spring 16, valve 58 is no longer positively kept open by engagement of stem 63 and abutment 64. In the

position of valve 58 shown in Figs. 1 and 2, valve element 60 shuts off passage 65 from passage 62 and as long as this is the case valve 58 cannot be opened by any pressure of gas in passage 62.

Gas under pressure that leaks to the top of valve element 60 is allowed to leak out from there to atmosphere through a permanently open passage 67 defined by coaxial bores in piston 15 and valve housing 59. Thus gas under pressure leaking to the upper surface of valve element 60 is precluded from exerting a valve opening pressure upon valve element 60 at any point of time at which valve 58 is supposed to stay closed. Gas under pressure that leaks to the lower side of valve element 60 is permitted to leak off from there to atmosphere through a permanently open leakage passage 67a. Passage 67a is defined by contiguous bores in piston 15 and valve housing 59. Thus gas under pressure leaking to the lower surface of valve element 60 is precluded from exerting a valve closing pressure upon valve element 60 at a point of time at which valve 58 is supposed to stay open.

In addition to stem 63, valve element 60 is provided with a stem 68 cooperating with an abutment 69 on cylinder base 14 for closing valve 58 by positive action when piston 15 of motor 1 completes the end of its stroke in a downward direction.

Stem 63 is being engaged by abutment 64 close to the end of the closing stroke of piston 15. There must be sufficient power behind piston 15 to insure engagement of main latch 27 and latch plate 31 before compressed air can be dumped from fluid motor 1. The moment the breaker 3 is restrained in closed circuit position by engagement of latching means 27, 31, any gas under pressure within the cylinder 12 of motor 1 can instantly be dumped completely. It may be advisable, in order to achieve this end, to arrange a plurality of dumping valves 58 along the periphery of piston 15 and to arrange in a similar way a plurality of dumping ports 66 along the periphery of cover plate 13 though, in the drawing, but one such valve and one such port has been shown for the sake of clarity and simplicity. If the latch mechanism 27, 31 performs properly upon closing of breaker 3 by fluid motor 1, the breaker will remain in closed circuit position, but dumping of gas under pressure through passage 62, valve 58, passage 65 and passage 66 will nevertheless occur and result in instantaneous high speed reversal of the movement of piston 15 to its position shown in Fig. 1. Piston 15, upon having reached that position, is ready to perform another closing operation.

It will be readily observed from the foregoing that initial opening of dumping valve 58 occurs irrespective of the condition of the circuit controlled by the breaker, and that dumping does not depend upon the proper operation of any electroresponsive trip device operable in response to any fault condition of the system into which the breaker is connected. Where the operation of a valve for dumping of compressed gas from the cylinder of a fluid operated circuit breaker operating motor is made dependent upon the presence of a fault condition in the electric system, the dumping valve does not afford any protection against the harmful consequences of a latch failure. Such an operating mechanism for circuit breakers would call for the provision of additional means for guarding against the harmful consequences of a latch failure, e. g., provision of an additional dumping valve which opens au-

tomatically when the supply of compressed gas is shut off from the breaker operating motor. It is apparent that the arrangement of the present invention requiring but one type of dumping valve is more simple, reliable in operation, and less expensive to manufacture.

It will be observed that the pressure of gas in passage 62, while able to maintain valve 58 in an open position upon initial opening of the valve, is unable to effect an initial opening of the valve. Initial opening of valve 58 requires its actuation by stem 63.

The biasing action of spring 61 is extremely light. Therefore valve 58 will remain open as long as there is but a small amount of pressure in the lower portion of cylinder 12 in excess of atmospheric pressure.

Although but one embodiment of the invention has been illustrated and described, it will be apparent to those skilled in the art that various changes and modifications may be made therein without departing from the spirit of the invention or from the scope of the appended claims.

It is claimed and desired to secure by Letters Patent:

1. In an operating mechanism for circuit breakers, a motor operable by fluid under pressure and comprising a cylinder and a piston movably arranged therein; a source of fluid under pressure; means for admitting fluid under pressure from said source to said cylinder to move said piston to a closed position; a collapsible linkage of the trip free type operated by said motor; latching means for restraining said linkage in a closed position; electroresponsive tripping means for releasing said latching means to cause collapse of said linkage; a first spring means for resetting said linkage upon collapse thereof; a plunger operated by said piston for operating said linkage to close the breaker; means for permitting return of said plunger and of said piston from a closed position to an open position irrespective of the position of said linkage; a second spring means for returning said plunger and said piston from a closed position to an open position; means including a piston type venting valve for said cylinder for permitting said second spring means to rapidly return said plunger and said piston from a closed position to an open position to permit said first spring means to rapidly reset said linkage; said valve further including means for biasing said valve to a closed position and means operative only upon initial opening of said valve by separate initial valve opening means for maintaining said valve in an open position by the action of pressure of fluid escaping through said valve; and separate initial valve opening means operating under the action of fluid under pressure supplied to said cylinder from said source and adapted to be operative during each stroke of said piston from an open position to a closed position upon reaching by said piston of a predetermined intermediate position.

2. In an operating mechanism for circuit breakers, a motor operable by fluid under pressure and comprising a cylinder and a piston movably arranged therein; a source of fluid under pressure; means for admitting fluid under pressure from said source to said cylinder to move said piston to a closed position; spring means within said cylinder for returning said piston to an open position; a collapsible linkage of the trip free type operated by said motor for closing

the breaker; means for restraining said linkage in a closed position; electroresponsive tripping means for causing collapse of said linkage; a ram on said piston separate from and cooperating with said linkage upon collapse thereof for reclosing the breaker; and means for instantly venting said cylinder not later than upon completion of each closing stroke of said piston; said venting means including a valve comprising a valve housing forming an integral part of said piston and a valve element movable relative to said valve housing, resilient means for biasing said valve element to a closed position, and means operative only upon initial moving of said valve element to an open position for maintaining said valve element in open position by the action of pressure of fluid escaping from said cylinder; zigzag passage means through said piston and said valve housing for venting one side of said cylinder to atmosphere; a stationary abutment; and an abutment on said valve element cooperating with said stationary abutment for causing initial opening of said valve during each closing stroke of said piston.

3. In an operating mechanism for circuit breakers, a motor operable by fluid under pressure and comprising a cylinder and a piston movably arranged therein; a source of fluid under pressure; means for admitting fluid under pressure from said source to said cylinder to move said piston to a closed position; spring means within said cylinder for returning said piston to an open position; a collapsible linkage of the trip free type operated by said motor for closing the breaker; means for restraining said linkage in a closed position; electroresponsive tripping means for causing collapse of said linkage; a ram on said piston separate from said linkage and cooperating with said linkage upon collapse thereof for reclosing the breaker; means for instantly venting said cylinder, said venting means including a piston type valve comprising a valve housing forming an integral part of said piston and a valve element movable relative to said valve housing, resilient means for biasing said valve element to a closed position, means defining a pair of permanently open leakage passages for venting both sides of said valve element to atmosphere and means operative only upon initial moving of said valve element to an open position for maintaining said valve element in open position by the action of pressure of fluid escaping from said cylinder; a stationary abutment; and an abutment on said valve element cooperating with said stationary abutment for causing initial opening of said valve during each closing stroke of said piston.

4. A circuit breaker comprising relatively movable contacts; spring means for biasing said contacts to an open position; a collapsible linkage of the trip free type for operating said contacts; latching means for restraining said linkage in a closed circuit position; a motor operable by fluid under pressure to operate said linkage, said motor comprising a cylinder and a piston movably arranged therein; a source of fluid under pressure; means defining a first passage for admitting fluid under pressure from said source to said cylinder to cause closing of said contacts; means defining a second passage for venting fluid under pressure from said cylinder to permit a rapid collapse of said linkage in case of opening of said contacts by said spring means on account of a failure of said latching means; and means for controlling the flow of fluid through

said second passage, said fluid flow controlling means including a valve forming a part of said piston; resilient means for biasing said valve to a closed position, means operative only upon initial opening of said valve for maintaining said valve in an open position by the action of fluid in said second passage, zigzag passage means through said piston and said valve interconnecting said passages, and separate means secured to said piston for causing initial opening of said valve irrespective of the condition of the circuit controlled by the breaker, said separate means being adapted to be controlled by the amount of the travel of said piston relative to said cylinder during a closing operation of said motor.

5. In an operating mechanism for circuit breakers, a motor operable by fluid under pressure and comprising a cylinder and a piston movably arranged therein; a source of fluid under pressure; means for admitting fluid under pressure from said source to said cylinder to actuate said breaker; a valve for rapidly venting fluid from said cylinder, said valve comprising a valve housing forming an integral part of said piston, a valve element movable relative to said valve housing, resilient means for biasing said valve element to a closed position, and means operative only upon initial opening of said valve for maintaining said valve in an open position by the action of fluid being vented through said valve; zigzag passage means through said piston and said valve housing for venting one side of said cylinder to atmosphere, said zigzag passage means comprising two sections each extending substantially longitudinally through a part of said piston and interconnected by a third section extending substantially perpendicularly to the axes of said valve and of said piston through said valve housing; and means for causing initial opening of said valve, said initial opening causing means comprising a member secured to said valve and actuated by said piston in dependence upon the extent of travel of said piston relative to said cylinder.

6. In an operating mechanism for circuit breakers, a motor operable by fluid under pressure and comprising a cylinder and a piston movably arranged therein; a source of fluid under pressure; means for admitting fluid under pressure from said source to said cylinder to actuate said breaker; a valve for rapidly venting fluid from said cylinder, said valve comprising a valve housing forming an integral part of said piston, a valve element movable relative to said valve housing, resilient means for biasing said valve element to a closed position, means defining a pair of permanently open leakage passages for venting both sides of said valve element to atmosphere, and means operative only upon initial opening of said valve for maintaining said valve in an open position by the action of fluid being vented through said valve; zigzag passage means through said piston and said valve housing for venting one side of said cylinder to atmosphere, said zigzag passage means comprising two sections each extending substantially longitudinally through a part of said piston and interconnected by a third section extending substantially perpendicularly to the axes of said valve and of said piston through said valve housing; and means for causing initial opening of said valve, said initial opening causing means comprising a member secured to said valve and actuated by said piston in dependence upon the ex-

tent of travel of said piston relative to said cylinder.
